UNITED STATES PATENT OFFICE.

JOSEPH D. WHITE, OF ALTOONA, PENNSYLVANIA.

DRAFT-SCREEN HOLDER.

SPECIFICATION forming part of Letters Patent No. 591,905, dated October 19, 1897.

Application filed January 13, 1897. Serial No. 619,071. (No model.)

To all whom it may concern:

Be it known that I, JOSEPH D. WHITE, a citizen of the United States, residing at Altoona, in the county of Blair and State of Pennsylvania, have invented a certain new and useful Improvement in Draft-Screen Holders, of which the following is a specification.

My invention relates to a new and useful improvement in holders and clamps for screens, papers, books, or the like, and has for its object to provide a simple and effective device which may be readily attached to the back of a railway-car seat and be utilized for the holding of a screen in the shape of a fan or similar article, so as to prevent a direct draft upon the person sitting in the rear of an open window.

Another object of my invention is to facilitate the holding of papers or books in such manner that they may be read without the labor of supporting the same in the hand; and with these ends in view this invention consists in the details of construction and combination of elements hereinafter set forth, and then specifically designated by the claims.

In order that those skilled in the art to which this invention appertains may understand how to make and use the same, its construction and operation will now be described in detail, referring to the accompanying drawings, forming a part of this specification, in which—

Figure 1 is a perspective of my improvement when adjusted for use; Fig. 2, a section thereof, the clip being turned at right angles to the position shown in Fig. 1; Fig. 3, a side elevation of my improvement when folded so as to be carried in a suitable case or a pocket; and Fig. 4, a perspective of the clip, when adjusted for use independent of the clamp, for a book or music holder.

In carrying out my invention as here embodied I provide the clamp A, which is composed of the two sliding members B and C, adapted to be adjusted upon each other, and a folding arm D, which is hinged at E to the member C, a stop F being provided for holding the arm at right angles to the member C for the purpose hereinafter set forth.

A holder G is pivoted at H to the member B so as to be held at right angles thereto by means of the lip I, and, as is obvious, when

this holder and the arm D are adjusted to the position shown in Figs. 1 and 2 the clamp may be secured to the back of a car-seat by 55 embracing the same, and it will be firmly held in place by moving the member C inward upon the member B, where it will be retained by the latch J, engaging with the depressions K. After the clamp has been thus 60 secured in place it will be seen that a fan, paper, or other object which would serve as a screen may be secured within the holder and so adjusted as to deflect the current of air flowing rearward from an open window, 65 which would otherwise become a serious menace to a person sitting therein.

The outer jaw L of the holder is provided with flanges M, adapted to receive the shank N, carrying a clip O, and this clip, which consists of a spring-actuated jaw arranged to bear against a stationary jaw, may be secured upon the holder in either a vertical position by its shank being passed between the clips or in a horizontal position by the shank being 75 passed through suitable slots formed in said clips, as clearly shown in Fig. 1, and when the clip is secured in either position it may be utilized for the holding of a book, paper, or other article, thus relieving the passenger 80 of the necessity of holding such article.

It is well known that the draft from a window does not blow directly upon the occupant of the seat next adjacent said window, and therefore persons without due consideration 85 for others may when occupying a seat in a car maintain an open window next their seat to the great annoyance and sometimes serious injury to people in the rear of said window, and, as this cannot well be regulated or prevented, the value of my improvement will be 90 obvious to those who are sensitive to a severe draft, since the effects thereof may be greatly modified if not overcome by the use of my improvement, and since the same may be folded 95 into a small compass and carried in the pocket, either in a case or without the same, much convenience will be experienced by the use thereof by such persons.

The device may be folded into a small compass, as shown in Fig. 3, by swinging the arm D inward against the member B, folding the holder G upon said arm, and placing the clip parallel with the holder, when the entire de-

vice may be slipped into a small case for convenience of carrying in the pocket.

As here shown, an extension P is pivoted at Q to the spring-actuated jaw O of the clip, 5 and to this extension is pivoted at R a swinging arm S, and these members are so arranged that the arm S may fold beneath the extension P, and the latter beneath the jaw O, and when thus folded the inturned ends of the 10 arm and extension serve to clasp the article held against the stationary jaw of the clip; but when desired this extension may be swung to the position shown in Fig. 4, where it may be utilized for the holding open of a 15 book, or music, or maintaining a paper in such a spread position that it may be easily read.

One of the advantages of my improvement is its exceeding simplicity and cheapness of manufacture and the fact that it may be 20 folded into such a small compass as to be readily carried in the pocket, so that when not in use it will not become cumbersome.

Having thus fully described my invention, what I claim as new and useful is—

25 1. As a new article of manufacture, a screen-holder, consisting of a clamp adapted to be adjusted to the back of a car-seat, a holder pivoted to said clamp, and a clip secured to said holder, as specified.

30 2. In a device of the character described, a

clamp, consisting of the members B and C arranged to slide upon each other and be secured in their adjustment, an arm D pivoted to one of the members, a holder pivoted to the member B, flanges M formed with the 35 holder, and a clip adapted to be secured to said holder by the flanges in either of two positions, as specified.

3. A screen-holder, consisting of a clamp adapted to be secured to the back of a car-seat, the holder G hinged to said clamp, a clip 40 adapted to be secured to the holder, and an extension pivoted to the movable jaw of the clip, said extension having an arm pivoted thereto, substantially as and for the purpose 45 set forth.

4. In combination with a clamp and holder of the character described, a clip, consisting of a shank N, a stationary jaw, a spring-actuated jaw, an extension pivoted to said jaw, 50 and an arm pivoted to said extension, substantially as and for the purpose set forth.

In testimony whereof I have hereunto affixed my signature in the presence of two subscribing witnesses.

JOSEPH D. WHITE.
